236,407

CONDIMENT DISPENSER

Morton Sape, Westport, Conn. (239 Danbury Road, Wilton, Conn. 06897), and George K. Maljanian, 67 Blue Ridge Road, Wilton, Conn. 06897

Filed Oct. 29, 1973, Ser. No. 410,434

Term of patent 3½ years

Int. Cl. D7—06

U.S. Cl. D7—52

FIG. 1

FIG. 2

FIG. 3

FIG. 4

FIG. 1 is a top plan view of a condiment dispenser showing our new design;

FIG. 2 is a side elevational view thereof;

FIG. 3 is a side elevational view thereof as seen from the right hand portion of FIG. 2, the opposite side being similar; and

FIG. 4 is a bottom plan view thereof.

We claim:

The ornamental design for a condiment dispenser, substantially as shown and described.
